United States Patent Office

Des. 229,640

Patented Dec. 18, 1973

229,640

FLUID DISPENSING COMB

Jacob Vander Meer, 662 Lake Drive SE,
Grand Rapids, Mich. 49503

Filed July 10, 1972, Ser. No. 269,984

Term of patent 14 years

Int. Cl. D28—03

U.S. Cl. D86—8

FIG. 1.

FIG. 2.

FIG. 3.

FIG. 4.

FIG. 5.

FIG. 6.

FIG. 1 is a side elevational view of a fluid dispensing comb showing my new design;

FIG. 2 is a top plan view;

FIG. 3 is a bottom plan view;

FIG. 4 is a front elevational view;

FIG. 5 is a rear elevational view; and

FIG. 6 is a perspective view.

I claim:

The ornamental design for a fluid dispensing comb, substantially as shown and described.
